UNITED STATES PATENT OFFICE

115,837

DESIGN FOR A CONTAINER FOR TOILET ARTICLES OR THE LIKE

William B. Petzold, Pittsfield, Mass., assignor to General Electric Company, a corporation of
New York

Application May 10, 1939, Serial No. 84,913

Term of patent 14 years

To all whom it may concern:

Be it known that I, William B. Petzold, a citizen of the United States, residing at Pittsfield, in the county of Berkshire and State of Massachusetts, have invented a new, original, and ornamental Design for a Container for Toilet Articles or the like, of which the following is a specification, reference being had to the accompanying drawing, forming a part thereof.

In the drawing:

Fig. 1 is a perspective view of the container for toilet articles or the like, showing my design in closed position; and

Fig. 2 is a perspective view thereof, in opened position.

I claim:

The ornamental design for a container for toilet articles or the like substantially as shown.

WILLIAM B. PETZOLD.
